(57) **CLAIM**

The ornamental design for a touch table, as shown and described.

DESCRIPTION

FIG. 1 is a perspective view of the touch table showing my new design;

FIG. 2 is a top plan view of the touch table of FIG. 1;

FIG. 3 is a side elevational view of the touch table of FIG. 1;

FIG. 4 is another side elevational view of the touch table of FIG. 1;

FIG. 5 is another perspective view of the touch table of FIG. 1;

FIG. 6 is yet another perspective view of the touch table of FIG. 1;

FIG. 7 is a perspective view of another embodiment of the touch table showing my new design;

FIG. 8 is a top plan view of the touch table of FIG. 7;

FIG. 9 is a side elevational view of the touch table of FIG. 7;

FIG. 10 is another side elevational view of the touch table of FIG. 7;

FIG. 11 is yet another side elevational view of the touch table of FIG. 7;

FIG. 12 is still yet another side elevational view of the touch table of FIG. 7;

FIG. 13 is another perspective view of the touch table of FIG. 7;

FIG. 14 is yet another perspective view of the touch table of FIG. 7;

FIG. 15 is a perspective view of another embodiment of the touch table showing my new design;

FIG. 16 is a top plan view of the touch table of FIG. 15;

FIG. 17 is a side elevational view of the touch table of FIG. 15;

FIG. 18 is another side elevational view of the touch table of FIG. 15;

FIG. 19 is yet another side elevational view of the touch table of FIG. 15;

FIG. 20 is still yet another side elevational view of the touch table of FIG. 15;

FIG. 21 is another perspective view of the touch table of FIG. 15;

FIG. 22 is yet another perspective view of the touch table of FIG. 15;

FIG. 23 is a perspective view of the touch table showing my new design;

FIG. 24 is a top plan view of the touch table of FIG. 23;

FIG. 25 is a side elevational view of the touch table of FIG. 23;

FIG. 26 is another side elevational view of the touch table of FIG. 23;

FIG. 27 is another perspective view of the touch table of FIG. 23; and,

FIG. 28 is yet another perspective view of the touch table of FIG. 23.

Broken lines shown in the drawings illustrate portions of the touch table and form no part of the claimed design.
